CIGAR WRAPPING MACHINE

Elmer L. Smith, Longmeadow, Mass., assignor to
Package Machinery Company, Springfield,
Mass., a corporation of Massachusetts

Application November 14, 1930, Serial No. 495,597

25 Claims. (Cl. 93—7)

Prior machines intended for the automatic wrapping of cigars have generally employed a wrapping material such as tinfoil or tissue paper which can readily be crimped or twisted to conform to the tapering shape of the cigar end. Recently the wrapping of articles in the transparent regenerated cellulose material known as cellophane has come into vogue, but prior to my invention it has been possible to wrap cigars in this material only by hand on account of the lack of any machine suitable for the purpose. On account of its high elasticity and the difficulty of forming permanent creases in it, this material could not be used in the wrapping machines previously employed for wrapping cigars in tissue paper or tinfoil. The problem is further complicated by the delicate nature and the varying shapes of the ends of the cigars, which prevent the formation of folds in the manner usual with other articles, in which the end of the article is generally used as a form.

It is the purpose of my invention to provide a machine which will wrap cigars of any usual shape in cellophane or similar material, without injury to the cigar ends and with the production of a neat and permanent end fold. While the fold employed has been used previously on other articles, the manner of its formation and the mechanism for producing it are novel. Preferably the cellophane used is of the moisture-proof variety, which carries on its surfaces thin films of a fusible waterproofing material. This material can be caused to retain a folded form by heat, and can to some extent at least be heat sealed; but it is difficult to handle mechanically on account of the impermanence of the folds until they are finally fixed in position by the heat treatment. The present machine is especially designed to handle this material, each fold being held positively after it is made until it is retained by succeeding folds or has been given permanence by the molding action of the final heat. The present application is a continuation in part of my copending application Serial No. 424,998, filed January 31, 1930.

The machine will now be considered in detail, and the purposes and advantages of individual mechanisms dealt with as the several devices are described. Referring first to the drawings:

Fig. 39 is a perspective detail of the mechanism for detecting improperly positioned cigars;

Fig. 40 is a detail of the mechanism for detecting the absence of a cigar taken on line 40—40 of Fig. 7; and

20 Fig. 41 is a view corresponding to a portion of Fig. 40 but with the parts in a different position of operation.

The machine, for purposes of compactness, carries the cigars through the several wrapping stages by grippers on an intermittently rotating turret. (See Fig. 19, in which the general path of the cigar through the machine is shown diagrammatically.) During the delivery of the cigar into the grippers a wrapper sheet is associated 25 with it. The cigars are carried into position adjacent the turret by any suitable device, shown in this case as an intermittently rotating disk having a series of cigar receiving pockets. A suitable automatic device, such as that shown in 30 my application for patent Serial No. 452,682, filed May 15, 1930, may be used to position the cigars initially in the pockets, or they may be placed there by hand. It may be assumed for the purpose of the present description that they are 35 manually fed. As the cigars are carried around by the disk they pass two detectors, one stopping the entire machine if a cigar is misplaced in its pocket, and the other causing the paper feed to skip an operation if a cigar is omitted from a 40 pocket. The paper feed may be of any desired type, the one shown feeding a web and cutting it off automatically to the desired length.

As they are being associated initially, the cigar and the cut wrapper are carried through a folding throat which drapes the wrapper around the cigar in inverted U-form (Fig. 21). As the partially folded package is grasped by the turret grippers, one depending flap is folded by a reciprocating plate, the other being tucked under 50 as the package is advanced through an arc of ninety degrees by the turret. At the second point of stoppage of the turret the now tubular extending ends of the wrapper are each formed with opposite bellows tucks, and the tucked ends 55 are compressed and bent down at right angles to the axis of the cigar (Fig. 27). Both the tucking and bending of the end extensions are done without using the end of the cigar as a form, and without exerting any damaging pressure 60 against it. At the third point of stoppage of the turret the end folds are bent under the cigar (Fig. 30), and as the wrapped cigars are ejected from the machine the folds are set and preferably sealed by the temporary application of heat. 65 The several mechanisms referred to will now be described in detail.

Cigar conveying turret

From a base 50 (Fig. 2, 4 and 9) rises a vertical 70 frame 51 and a pair of spaced tie rods 52, carrying

at their top a horizontal support plate 53. A turret shaft 54 is journaled both in the base and in the support plate, being held against vertical movement by collars 55 (Fig. 9) above the former and below the latter. Rigidly secured to the upper end of the turret shaft is a head 56 (Figs. 1, 5, 13 and 24), provided with upper bearings 57 arranged in aligned pairs and lower bearings 58 similarly paired but having their axes at right angles to those of the upper set. Journaled in the upper bearings are a pair of gripper carrying shafts 59. Similarly journaled in the lower bearings are a pair of gripper carrying shafts 60, the two sets of shafts crossing each other. The shafts bear at their ends depending arms 61 carrying elongated flat gripper plates 62 at their lower ends. The arms attached to the upper shafts 59 are enough longer than those on the lower shafts 60 to compensate for the difference in elevation of the shafts, so that all the grippers travel at the same level.

A short arm 63 (Fig. 24) carrying a roller 64 is fixed to each end of each shaft just outside its bearing in the head 56, restraining the shaft against endwise movement and affording means 105 for rotating it. These arms are thus arranged in pairs, each pair being joined by a spring 65 stretched between pins 66 on the arms. Abutments 67 are formed on each arm with the abutments of each pair coming in contact under the 110 pull of the spring when the grippers are in closed position. A wedge 68 (Figs. 2, 5 and 6) is formed upon the upright end of a lever 69 pivoted at 70 in a bearing 71 secured to the plate 53. The wedge normally lies inside the path of rotation of the 115 rollers 64 at the point where the grippers stop at the third wrapping stage. Once at each stoppage of the turret the wedge is forced outwardly between the rollers to separate them and thus open the grippers momentarily. Not only are the grippers at the third station opened by this action, but also the grippers at the first station directly opposite; opposite pairs of grippers at all times 120 moving together on account of the rigid shaft connection between them. The lever 69 carries at its 125 end remote from the wedge a cam roll 72 running against a disk cam 73 fixed to a vertical cam shaft 74 journaled in the base 50 and the plate 53. A spring 75 is stretched between the roll end of the lever and a vertical rod 76 holds the roll constantly against the cam.

Turret rotating mechanism

Secured to the turret shaft 54 is a Geneva wheel 80 (Figs. 8 and 9) having four radial slots 81 and peripheral locking recesses 82. A series of three rolls 83 mounted on the surface of a gear 84 fit successively into the slots 81, and projecting locking members 85 secured to the same gear fit into the locking recesses. Gear 84 meshes with a 125 pinion 86 (Figs. 4 and 8), the shaft of which is secured by mitre gears 87 with the shaft 88 of a reducing gear box 89. This box is connected through a clutch 90 with an electric motor 91. These driving parts may be of any standard 130 design and need not be described in detail. Assuming the clutch engaged, constant rotation of the motor will cause intermittent rotation of the turret shaft, the latter moving through a quarter turn and then halting. The cam shaft 74 carries 135 a pinion 92 meshing with the gear 84 and thus is rotated continuously.

Cigar feed disk

The cigars are carried to the first wrapping 140

station by a feed disk 100 shown in plan in Fig. 7 and in section in Fig. 13. This disk is secured to the upper end of a vertical shaft 101 journaled in the base 50 and the plate 53. A Geneva disk 5 102 (Figs. 8 and 9) is secured to the lower end of this shaft, with radial slots 103 and peripheral locking recesses 104. A short vertical shaft 105 is joined by a pinion 106 with the constantly rotating gear 84. Upon the upper end of the shaft 10 105 is an arm 107 carrying a roll 108 which enters the slots 103 and a circular abutment 109 which engages the recesses 104. The feed disk 100 is thus rotated intermittently a sixth of a revolution 15 at a time. The gearing is so proportioned that the turret moves a quarter and the disk a sixth of a revolution at the same time.

Referring particularly to Figs. 7 and 13, the disk is provided with a series of six generally rectangular pockets 110 each large enough to receive a single cigar. One end 111 of each pocket is preferably made straight and the other end 112 slanting. Underlying each end of each pocket is a cigar supporting plate 113. As a cigar is placed in each pocket one end slides down the incline 112 25 a distance depending upon the length of the cigar, insuring that the other end strikes the flat end 111 of the pocket. This gives to one end of the cigar a definite position in the machine, preferably chosen so that it is the one adjacent the shears which cut off the paper. This is for the reason that it is easier to vary the length of paper fed, and thus control the amount of paper which projects beyond the shears, than it is to change 30 the position of the shears. Slight inequalities in the lengths of cigars are thus accommodated 35 while preserving the registration of one end of the cigar with the position of the cut wrapper.

Wrapper feed

Wrappers may be fed to the machine by hand 40 or by any suitable mechanical web or sheet feed. In the present case a web feed is illustrated. The paper or cellophane web *w* (Figs. 3 and 13) is carried from a roll under the usual slight tension 45 over a pair of idle rolls 115 and 116 having edge-guiding flanges 117 (see also Fig. 1). From these rolls the wrapper web is received on a table (Figs. 1, 13 and 38) having a horizontal top 118 and 50 slanting sides 119. The top 118 is at one point cut away as at 120 (Fig. 13) so that a lower paper feed roll 121 may pass through it into contact 55 with the paper. This roll is fixed to a shaft 122 journaled in the frame and connected by a universal joint coupling 123 (Fig. 1) with a shaft 124. This shaft is connected by gearing 125 with 60 a transverse shaft 126 which has fixed to it a pinion 127 (Fig. 3) meshing with a gear 128 on a short shaft 129. Affixed to the gear 128 is a ratchet wheel 130. A plurality of pawls 131 (Fig. 2) are mounted upon a pawl carrier 132 journaled 65 upon the shaft 129 and having a slotted arm 133 projecting from it. A pivot 134 is adjustably secured in the slot of arm 133, and is joined by a link 135 with a rocking lever 136 pivotally carried 70 upon a transverse support shaft 137. This lever is rocked periodically by mechanism to be described, and rotates the lower feed roll 121 intermittently an amount depending upon the setting of the adjustable pivot 134. The plurality of pawls 131 are spaced apart by distances slightly greater or less than a multiple of the spacing of the ratchet teeth, so that the adjustment can be made finer than that corresponding to one 75 tooth of the ratchet, as is well understood.

Returning now to the paper engaging rolls, the lower roll 121 is supplemented by an upper roll 140 (Figs. 1, 3, 13 and 38) fixed to a shaft 141 journaled in a frame 142 swinging on a supporting shaft 143. A spring 144 (Fig. 1) assists the weight of the parts in pressing the upper roll upon the paper. The shaft 141 carrying the upper roll is connected to the shaft 122 carrying the lower roll by gearing 145 so that they rotate together. A brake 146 is also preferably applied to the upper roll shaft so that there will be no tendency to over-run or to pull back during the backward movement of the pawls.

In dealing with wrapping material of the thinness of cellulosic material such as cellophane, it 80 is desirable to prevent it from buckling as it is projected by the feed rolls across the cigar to be wrapped. In the present case this result has been accomplished by arching the paper as it is fed by the rolls 121 and 140. It is for this reason that the table over which the web is fed is provided 85 with the slanting sides 119. Frustoconical rolls 147 (Fig. 38) are mounted upon shaft 141 adjacent each side of the roll 140 to assist in shaping the sides of the web to the angle determined by the 100 sloping table sides 119. In this they are assisted by guide rails 148 and plates 149 secured thereto.

Positioned adjacent the termination of the table 118, 119 are a pair of shear blades 151 (Figs. 1, 10, 13 and 38) pivoted at 152 (Fig. 10) and 105 having operating extensions joined by links 153 with a lever arm 154 projecting from a shaft 155. The other end of this shaft carries an arm 156 (Figs. 1 and 10) joined by a link 157 with a lever 158 (Fig. 8) pivoted at one end to the support 110 shaft 137 and carrying a cam roll 160. The lever 158 is held down by a spring 161 so that the roll 160 will ride at all times upon the surface of a cam 162 (Figs. 3 and 8) mounted near one end 115 of a horizontal cam shaft 163. At its other end this shaft is joined by gearing 164 with the shaft 88 extending from the gear box. By this mechanism the shears are actuated to cut off a length 120 of paper once during each cycle of the operation of the machine, this operation occurring just after the feed of the paper has been stopped and after the paper has been clamped between the cigar and a holding plunger as will be described below.

Beyond the shear blades the central part of the 125 wrapper is supported by spaced guide bars 165 (Fig. 10), and its edges are received by side guides 166 having paper receiving slots 167. These guides are formed with a U-shaped body having unequal legs 168. Each leg is bolted through a 130 slot 169 formed in a bracket member 170, so that they may be adjusted for different paper widths. Slanting plates 171, cooperating with the bars 165 and the guides 166, and shown in Figs. 10, 20, and 21 are preferably provided, affording additional support to prevent buckling of the paper. In order to permit changes in the amount which the wrapper projects at the end of the cigar, the wrapper feeding mechanism, including the feed rolls and shears, is preferably mounted upon a 135 separate bed 172 (Figs. 7 and 13) having sliding connection with a guide bar 173 on the plate 53 and held down in adjusted position by a slot and bolt connection 174. Adjustment of the amount the wrapper projects beyond the end of the cigar 140 at the left in Fig. 13 is obtained by shifting the paper feed bodily, thus changing the distance between the cigar and the shears. Similar adjustment at the other end of the cigar is obtained 145 by adjusting the pivot 134, which changes the 150

length of paper projected beyond the shears at each operation.

First wrapping station

5 The disk 100 at each stoppage locates a cigar directly below the end of the paper web which has been projected past the shears by the rotation of the paper feed rolls. At this point the cigar is removed from the disk by an elevating 10 plunger 180 (Figs. 7, 10, 13 and 20) carried upon a vertically reciprocating rod 181. The rod slides in bearings 182 (Figs. 3 and 9) and has a forked arm 183 extending from it and embracing the disk shaft 101 so that the rod may slide without 15 rotation. A bracket 184 is adjustably secured to the rod as by a set screw 185 and has pivoted to it a pair of links 186 straddling the rod and pivoted in turn to one end of a lever 187 pivoted in its middle upon the support shaft 137. A spring 20 188 (Fig. 3) acting upon the link end of this lever holds a cam roll 189 on its other end against the surface of a cam 190 (Figs. 3 and 8) fixed to the cam shaft 163. The plunger 180 is by this mechanism given one complete up and down reciprocation during each cycle of the machine, its motion being completed during the intervals of rest 25 of the disk 100 so that the plunger may pass successively through the pockets 110.

Cooperating with the lower plunger 180 is an 30 upper plunger 200 (Figs. 20 and 21) having a vertical reciprocation from the position shown in Fig. 20, where it is substantially in contact with the paper carried on the guide bars 165, to that of Fig. 21, where the cigar and paper are delivered 35 between the gripper plates 62. The upper plunger 200, as best shown in Fig. 13, is formed on the lower end of a bent arm 201. Levers 202 and 203 are pivoted to the upper end of this arm and to a bracket 204 to form a parallel motion 40 linkage, so that the arm 201 may have a vertical motion relative to the bracket while maintaining the bottom of the plunger 200 always horizontal. This motion is used to permit a vertically 45 yielding motion of the plunger to accommodate slight differences in cigar thicknesses and to secure the desired pressure between the cigar and the paper lying over it. For this purpose the lever 203 has a rearwardly extending portion 205 joined by a spring 206 with a lug 207 on the bracket 204. Another lug 208 on the bracket underlies a cross piece 209 on the link 202 in order to 50 limit downward motion of the plunger relative to the bracket.

The bracket 204 is fixed on a vertical shaft 210 55 journaled in a yoke 211 (Figs. 10, 11 and 13) carried on the top of a vertically reciprocable rod 212. A torsion spring 213 has one end fixed to the yoke and the other end fixed to a collar 214 on the shaft 210, operating to hold the lug 207 normally 60 against a lug 215 on the yoke. In the normal functioning of the machine the bracket 204 acts as if integral with the yoke. If, however, the plunger 200 should get caught by the gripper plates 62 in their rotation the spring connection 213 permits it to be rotated by the grippers until it pulls 65 loose, thus preventing breakage of the parts. The rod 212 is adjustably connected at its lower end with a bracket 216 (Figs. 3 and 9) which is coupled by a link 217 with a lever 218 pivoted on the shaft 159 and having a cam roll 219 resting on the surface of a cam 220 carried by the cam shaft 163.

As the lower plunger 180 raises a cigar out of 70 one of the pockets 110, it carries it against the wrapper, which is draped over the supporting

bars 165 (Fig. 20) and then presses the assembly against the upper plunger 200. As soon as firm contact has been made, resulting in a slight stretching of the spring 206, which preferably assists the weight of the parts in holding the wrapper against the cigar, the yoke 211 is raised by its cam mechanism at substantially the same speed as the lower plunger. This permits the upper plunger to continue to rest on the wrapper as the partially wrapped cigar is carried between the gripping plate 62. When the cigar and its wrapper are presented to the grippers, the latter are partially open to permit easy entrance. The grippers close, however, while the cigar is still traveling upwardly exerting a frictional drag on the wrapper which draws it tightly around the upper surface of the cigar. The upward motion of the upper plunger is then continued by its operating cam to clear it from the path of the grippers. The lower plunger at the same time descends to clear it both from the grippers and from the cigar feeding disk 100.

When a cigar is brought to rest by disk 100 in a position in line with the plungers 180 and 200, the lower plunger is just below the disk, the end 100 of the paper web (at this time still uncut) lies over the guide bars 165 with its edges held in the slots 167 of the side guides 166, and the upper plunger 200 is at its lowermost position immediately above the paper. This condition is shown 105 diagrammatically in Fig. 20. The lower plunger then rises to elevate the cigar into contact with the paper and the upper plunger, the end of the wrapper web is cut off, and then both plungers rise, carrying the cigar through a preliminary 110 folding chute which drapes the wrapper in U-form around the cigar. This chute is composed of spaced side walls 221 (Figs 10, 12, 13, 20 and 21) formed on the brackets 170 and having flaring 115 bottoms 222 to facilitate the entrance of the cigar and wrapper between them. At their upper portions, these walls are cut away as at 223 (Figs. 12 and 13) to form a recess in which plates 224 are located. These plates are attached by a flat 120 spring 225 to the walls 221, so that they have a normal tendency to project into the chute in the manner shown in Figs. 10 and 12. Their motion into the chute is, however, limited by stop 125 screws 226 threaded into sidewardly extending lugs 227 formed on the plates and overhanging the adjacent side walls. Lock nuts 228 permit the setting of the screws to be maintained in any desired position of adjustment. As the cigar and 130 wrapper are elevated the plates exert a spring pressure upon the sides of the wrapper to pull them snugly around the cigar as it passes between them into the grippers waiting just above.

The cigar is now positioned in the grippers 62 as in Fig. 21 with a rear flap *a* and a front flap *b* hanging down below it. The rear flap is folded 135 up against the bottom of the cigar by a reciprocating plate 230. Bearings 231 (Figs. 1 and 10) formed on the bottom of the plate are slideable on rods 232 fixed to the frame and are provided with a rearwardly extending support 233. A link 234 140 is pivoted at one end to the plate 230, its other end overlying the support 233 in the normal operation of the machine. A pin 235 passes freely through the link and is fixed by a set screw 236 in one arm of a bell crank lever 237. This lever, 145 which is pivoted at 238 to the frame, carries a roll 239 running against the surface of a cam 240 fixed upon the vertical cam shaft 74. The plate 230 is by this mechanism reciprocated once during each machine cycle across the top of the folding chute. 150

As the plate moves, the grippers also are moved by the rotation of the turret, carrying the cigar in a curved path across the surface of a flat arcuate table 241 (Figs. 22 and 23). The under side of the 5 plate is beveled as at 242 and the upper side of the table is beveled as at 243 so that the plate may overlap the table slightly as shown in Fig. 22 and assist in tucking the fold *a* under the fold *b*. When it is desired to remove the folding plate 230 10 for cleaning or for removing a crumpled wrapper, the lever 237 is rocked back manually against the action of its spring 244 (Fig. 2) until the bearings 231 are clear of the rods 232, which form an open ended stationary guide upon which the bottom 15 folder reciprocates. The whole plate assembly, including the bearings 231, the support 233, and the link 234, can now be removed without any difficulty, owing to the absence of any permanent connection between the pin 235 and the link. It 20 is for this purpose that support for the rear end of the link is furnished by the member 233 rather than by a pin or collar connection with the pin 235.

Second wrapping station

25 A quarter turn of the turret brings the cigar, with the wrapper now folded around it in the form of a tube extending beyond it at each end (Fig. 23) to a second stage indicated at B in 30 Figs. 1 and 19 and shown in perspective in Fig. 24. Here a pair of bellows-like side tucks *c* (Fig. 25) are made in each tubular projecting end extension of the wrapper and the end folds are started. The side tucks are made by two pairs 35 of plates 250, one pair being located beyond each end of the cigar as shown in Figs. 24 and 25. One pair of these plates has been shown in plan in Fig. 18. The cigar engaging end of each plate is tapered as at 251 to correspond 40 roughly at least with the shape of the end of the cigar. These portions of the plates make the shallow part of the bellows folds adjacent the cigar, gradually deepening the fold to correspond with the shape of the cigar. Just beyond the end of the cigar the two plates of a pair 45 nearly meet so as to bring the opposed tucks nearly into engagement with each other. The edges of the tucking plates in this area are beveled as at 252. To assist in flaring the 50 bellows folds neatly and symmetrically into the body of the wrapper, as indicated at *d* in Figs. 25 and 27, the plates are preferably enlarged or thickened at their ends as at 253 (Fig. 24). The 55 increased area of contact with the wrapper resulting from this enlargement adds to the appearance of the finished article by giving a more definite location to the flaring part of the 60 folds.

The tucking plates are carried on rocking levers 65 255 (Figs. 14, 15 and 24) fixed upon parallel shafts 256 extending between the two pairs of folders. The levers, and consequently the plates carried on their ends, are rotatable through arcs having the shafts 256 as centers so that the 70 plates swing from their wrapper engaging positions shown in full lines in Figs. 14 and 24 to an inactive position shown in dotted lines in Fig. 14. During this swinging motion the plates travel through notches 257 in the table 241, so that 75 they may recede entirely out of the way of the cigars being advanced by the grippers over the surface of the table. The levers 255 forming one pair are geared together as at 258 and one of them has an extension 259 (Figs. 14 and 15) joined by a link 260 with one end of a rocking 80 lever 261 pivoted on the top plate 53 at 262 and having a roller 263 running against a cam 264 on the vertical cam shaft 74. A spring 265 holds the cam roll against the cam. By this means the opposed pairs of tucking plates 250 are swung towards each other once during each cycle to form bellows-like side tucks extending towards each other in each projecting tubular end 85 extension of the wrapper.

At the same wrapping station at which these tucking plates act upon the wrapper are additional pairs of folding members which preserve the bellows folds from opening out and partially complete the end folds in a manner which gives to the wrapper end a fold line or hinge spaced from the end of the cigar. On account of the delicate nature of the end of a cigar and on account of the variation in end contour between cigars of varying makes and types, it is desirable to form the end folds without using the end of the cigar as a template. It is also desirable to avoid pressing against the tobacco near the cigar end either with the folding devices or with the wrapping material as this is being drawn around into final fold form. To this end the folding members which are now 100 to be described do their own folding of the wrapper without contacting with the cigar or depending upon it to give end shape to the wrapper; and furthermore leave in the wrapper a wrapper-supported hinge around which the final fold may 105 be made.

The end folding members forming this second set are likewise arranged in pairs, one at each end of the cigar. Each set comprises an upper roller 270 and a lower plate 271 (Fig. 24) both 110 the roller and the plate being vertically reciprocable. The roll actuating mechanism will be described first. Located at wrapping station B is a U-shaped vertically reciprocating carrier 272 (Fig. 15) having its cross piece extending underneath the table 241 and its parallel arms rising above the table at each side. Each of these arms carries a bracket 273 preferably held adjustably in place by a set screw 274 (Fig. 17). In each of these brackets a link 275 is pivoted at 276, 120 and has an angularly extending arm 277 adapted to rest upon the top of the bracket to limit the swinging motion of the link. A roll 270 is rotatably mounted on the lower end of each link. In each of the brackets is formed a recess 278 125 in which a disk 279 slides under the influence of an adjusting screw 280. A spring 281 is compressed between the disk 279 and the link 275 so that the rolls are forced with a controllable pressure towards its corresponding folding plate 130 271. The carrier 272 is attached to the upper end of a rod 282 (Fig. 15) fixed on a slide 283 vertically movable on a rod 289. A link 284 is attached to the slide, connecting it to an adjusting slot 285 (Fig. 4) in the end of a lever 135 286 swinging upon the support shaft 137. A cam roll 287 secured to this lever rolls upon a cam 288 (Figs. 3 and 8) on the horizontal cam shaft 163. A rod 289 (Fig. 15) is connected to the carrier 272, passing freely through a hole in the plate 53 to prevent the carrier from rotating. The rolls 270 are by this mechanism elevated and lowered once during each cycle of the machine, with a detailed motion and a coaction with the plates 271 which can be explained best below. 140

Each of the plates 271 is preferably vertically slotted at 290 (Fig. 24) so that it may be adjustably attached by screws 291 to a block 292. The block is in turn secured by screws 293 (Fig. 16) passing through horizontal slots 294 in a 145

carrier 295. The carrier is fixed upon the end of a rod 296 attached at its lower end to a slide 297 movable upon the tie rod 52 previously mentioned. A link 298 joins the slide with a lever 299 (Fig. 8) pivoted upon the support shaft 137 and bearing a cam roll 300 running against a cam 301 on the cam shaft 163.

The roll and plate of each pair move towards each other in a vertical direction, so that they engage the wrapper end extension at points between the tucking plates. The cams controlling the motions of the parts are set to cause the wrapper to be pinched between the roll and plate at a time prior to the withdrawal of the tuckers, so that the tucks are fully formed, the wrapper is at all times under the control of some folding member, and the folds are kept imprisoned to prevent the resilience of the material undoing the folding previously done. This tendency to spring back is so pronounced when a resilient material such as moisture-proof cellophane is used that especial wrapping difficulties are developed. The present machine has been designed with particular reference to these difficulties, and it will be noted that the folds are at all times held against springing back until the final heat treatment gives the cellophane a permanent set in its folded condition.

As the tucking plates 250 are withdrawn, the plates 271 are elevated to approximately the longitudinal axes or median plane of the cigar, and the rolls 270 are lowered; causing the entire tucked wrapper end to be folded over as in Fig. 26 and pinched between the edges of the plates 35 and the rolls under the pressure of springs 281. The plies of the wrapper ends are thus superposed or brought into contact, and the superposed plies of each end extension are given a transverse crease or fold *e* (Fig. 27) which in subsequent folding operations acts as a hinge. The plates 271 are adjusted so as to be slightly spaced from the ends of the cigar, resulting in the fold lines *e* being also so spaced. These fold lines or hinges are supported by a pyramidal wrapper structure consisting of the upper and lower tapering ends and the flaring portions *d* of the bellows folds. The continued lowering of the rolls 270 causes them to pass completely over the end folds, as shown in Fig. 26, folding and creasing the edges of the bellows folds against the flat sides of the plates 271. These plates, as well as the rolls 270, are made wider than the end folds. The plates then descend, the rolls remaining in their lowered position so that their links 275 hold the creased end flaps against their normal tendency to spring back. With the links still in lowered position, the grippers again make a partial rotation, carrying the cigar from station B to a third station C (Figs. 1 and 19). During this travel of the cigar the end flaps are received in annular grooves 302 (Fig. 1) formed between the sides of the table 241 and curved guide plates 303.

Third wrapping stage

The grippers carry the partially wrapped cigar from the second stage mechanism through an arc of ninety degrees over the plate 241 to the third stage devices. A plunger 310 (Figs. 28 and 31) is vertically reciprocable by mechanism to be described from the position of Fig. 31, where it is level with the surface of the plate 241, to the position of Fig. 33 in which it is substantially level with a heated discharge plate 311. In its upper position it forms in effect a continuation of the

plate 241, the grippers 62 completing their ninety degree movement with the cigar positioned upon the top of the plunger as shown in Fig. 32. In order to insure a continuous tension on the bottom folds of the wrapper the plunger is preferably provided with separate end pieces 312 (Fig. 36) mounted on rods 313 slidable in the plunger and pressed upwardly by springs 314. An upper limit of motion of the end pieces is set by pins 315 which strike against the rod bearings. The side of the end pieces facing the advancing cigar is beveled as at 316 (Fig. 31) to facilitate the cigar riding upon it. In their upper position the end pieces are normally slightly above the level of the plate 241 and the plunger 310, as seen in Figs. 31 and 36. The cigar is carried by the grippers over the plunger and onto the end pieces, depressing them against the force of their springs so that they exert a resilient holding action on the bottom folds.

As stated above, the downwardly extending end folds *f* are held by the side guides 303 during the transportation of the cigar by the grippers. After leaving the guides the end folds are received between a pair of brackets 317 (Fig. 34) forming in effect a continuation of the side guides. The lower ends of the brackets are curved inwardly as at 318 (Fig. 36) with a shape corresponding roughly to that of the cigar ends. The brackets 317 are slotted as at 319 (Figs. 35 and 36) to pass and guide the shanks 320 (Figs. 34 and 36) of vertically reciprocating top holding members 321, also shaped to conform to the cigar ends. The shanks of these members are each adjustably held in one arm of a U-shaped carrier 322 by a cap 323 and screws 324 passing through slots 325 (Fig. 34) in the carrier arms. At its central portion the carrier is formed into or otherwise supports the plunger 310, so that the plunger and the top holding members move up and down in unison. The carrier 322 is fixed to rods 326 (Figs. 2 and 3) vertically slidable in fixed bearings 327. A yoke 328 joins the lower ends of the rods, and is connected by a link 329 (Fig. 2) with a lever 330 pivoted to a stationary bearing 331 on one of the vertical tie rods 52. Upon the lever is a cam roll 332 held by a spring 333 against the surface of a crown cam 334 on the cam shaft 74.

As the cigar moves from the position of Fig. 31 to that of Fig. 32 it forces the end pieces 312 downwardly against the force of their springs 314. During this motion the ends of the cigar pass under the overhanging members 321, and to permit this the members must be spaced from the upper surface of the plunger 310 a distance sufficient to afford a clearance, as shown in Fig. 28. When the grippers 62 separate, the end pieces 312 exert a steady pressure on the bottom of the cigar, and force it up until its ends strike the members 321. The body of the cigar is now slightly spaced from the surface of the plunger 310, but the bottom folds *a* and *b* are held by the spring pressure back of the end pieces 312.

As the carrier 322 descends, the cigar, now released by the grippers 62 and held lightly between the end pieces 312 and the top members 321, will be brought down against the folders 318 (Fig. 29). The end folds *f* will strike the curved surfaces of the folders 318 end on, and will be turned around the hinge line *e* onto the bottom of the cigar. There is in this preferred form no plow action as is usual in folding devices, but an end-on action which is permitted by the character of the wrapping material and the backing given by the shaped top holding members 321.

In the position thus reached, indicated also in Fig. 33, the completely wrapped but unsealed cigar is in line with the heating plate 311 which is kept hot by an electric element 335 of usual form.

- 5 An ejector 336 is pivoted to a long lever 337 (Fig. 2) and a short lever 338 both having bearing on the frame of the machine. As these levers are rocked the end of the ejector is caused to travel with a straight line motion. A link 339 couples with an intermediate point of the lever 337 with a lever 340 pivoted to the machine and bearing a cam roll 341 engaging a cam 342 on the cam shaft 74. The ejector is actuated by this mechanism once during each wrapping cycle to clear the wrapped article 10 from between the top members 321 and the folders 318 and carry it onto the heating plate 311.

It is desirable to hold each article delivered to the heating plate snugly against the one ahead of it in order to hold the folds in place until they 20 have become set. Any retrograde movement of the newly positioned article would of course remove this holding pressure. To prevent this, a pair of spaced pins 345 (Figs. 32, 33 and 37) are provided which normally extend through holes 25 346 (Fig. 37) in the heating plate against the rear of the rearmost article in the delivery channel. The pins are mounted in a carrier 347 fixed to the upper end of a rod 348. At its lower end this rod is joined (Fig. 2) to a lever 349 pivoted to 30 the tie rod 52 and drawn upwardly by a spring 350. This spring keeps a cam roll 351 on the lever against a crown cam 352 on the cam shaft 74. As the ejector is moved ahead (Figs. 32, 33 and 35) the pins are lowered, receding below the 35 surface of the plate in time to avoid interference with the cigar being advanced by the ejector. Before the ejector starts its rearward motion, the pins are raised, holding the rearmost cigar as the 40 ejector returns to its inactive position. To permit this action the ejector is made narrower than the space between the pins.

The heating plate 311 is provided with side members 353 (Fig. 37) which are curved to fit the ends of the cigar similarly to the folders 318. 45 These side members are preferably heated by conduction from the plate 311. The heat thus supplied causes the end folds to lose their elasticity, and as the wrappers are cooled in their subsequent motion through the delivery channel these 50 folds become set in their folded condition. While in the delivery channel the articles are pressed closely together, so that each article supports the bottom folds of the one next to it against opening up. The heat is preferably sufficient so that 55 when moisture-proof cellophane is used as a wrapping material the folds will not only be molded into form but will also be stuck together by adhesion of the melted coating.

The delivery channel comprises a plate 354 (Figs. 1 and 2) fitted with side guides 355, which 60 may be curved similarly to the member 353 but are preferably in the form of vertical flanges as this has in practice been found sufficient to prevent opening up of the sealed flaps. Over a portion 65 of the delivery channel is a top plate 356 supported upon a handle casting 357. Rods 358 extending sidewardly from the handle casting fit into open slots 359 formed in brackets 360 rising from the channel plate. A spring-pressed latch 70 361 may be provided to retain the top plate in position and yet to permit its ready removal whenever desired. An elastic fabric strip 362 (Fig. 75) may be mounted underneath the top plate to reduce friction and to prevent scratching by metal

surfaces of the cellophane-wrapped articles passing below it.

Detector for mispositioned cigars

In order to prevent jamming of the machine in case a cigar is improperly positioned in a pocket 110 of the disk 100, a detecting mechanism is provided, actuated by an improperly seated cigar to stop the entire machine. This device operates by tripping the hand lever 370 (Figs. 2, 7, and 8) which controls the clutch 90 and is fixed to a shaft 371 extending across the machine. An arm 372 projects downwardly from the shaft and is connected by a link 373 with the shifting lever 374 of the clutch. The clutch shifting mechanism may be of any desired type, not constituting in itself a part of my invention. It is therefore not described in detail. A spring 375 is stretched between the link 373 and a fixed point on the machine, giving to the clutch a normal tendency to disengage, a tendency resisted during the normal operation of the machine by a releasable latch carried upon the top end of the lever 370, as will now be described.

Pivoted at 376 (Fig. 9) to the upper end of the hand lever 370 is a latch bar 377 provided with a shoulder 378 and a notch 379 adapted to engage a bar 380 secured to the frame. A pin 381 pivoted to the latch bar passes through the handle portion 382 of the lever 370, and has an enlarged upper projecting end which is pressed upwardly by a spring 383. The hand lever is shown in Fig. 9 in position to disengage the clutch, being held against accidental displacement by the engagement of the shoulder 378 with the bar 380. By depressing the projecting end of pin 381 the hand lever may be swung to clutch engaging position, whereupon the latch bar will be drawn up by its spring to cause engagement of the notch 379 with the bar 380. The clutch will then be held in engaged position until released either by hand or by the following automatic device.

Referring particularly to Figs. 7 and 39, a shaft 385 is journaled in brackets 386 carried by the plate 53. One end of this shaft lies adjacent the disk 100 and carries a bell crank 387 having a cigar contacting plate or feeler 388 on one arm. The other arm of the bell crank is adapted to strike a stop screw 389 to limit the rocking movement of the shaft in one direction. Also attached to the shaft is an arm 390 (Fig. 39) carrying a stud 391 with an enlarged end engageable with the upper side of the latch bar 377. A stop screw 392 is positioned in the path of arm 390 to limit its downward motion. Upon the end of the shaft 385 opposite the feeler 388 is a crank 393 having its end joined by a spring 394 with a lug 395 on the plate 53. The lug and crank are so positioned that the spring passes substantially across the axis of the shaft, the shaft being thus held either with the arm 387 against the stop 389 or with the arm 390 against the stop 392.

With the parts in the positions shown in Fig. 39, the lower end of the slantingly held feeler 388 lies just above the intermittently rotated disk 100 in line with the pockets 110 (see also Fig. 9). As long as the cigars are fully seated in the pockets there will be no effect upon the feeler or its connected mechanism. If, however, one of the cigars is improperly positioned, the feeler will be tilted up, and the spring 394 will snap the shaft over to its other extreme position. In this motion the stud 391 will knock the latch bar 377 down, disengaging the notch 379 from the bar 380 and permitting the spring 375 to dis-

engage the clutch. After the operator has corrected the error in positioning the cigar, the machine may be restarted manually.

5 *Paper feed control*

In considering the mechanism for imparting oscillatory movement to the pawl carrier 132 and hence for intermittently rotating the paper feed rolls, description of the means for oscillating the lever 136 was deferred. This description will now be resumed in connection with the devices for causing the paper feed to miss in the absence of a cigar to be wrapped. The lever 136 is in the form of a bell crank (Figs. 40 and 41) one arm of which is coupled to the link 135 and the other of which carries a cam roll 400. The roll is urged by a spring 401 towards a cam 402 on the horizontal cam shaft 163, it being the spring 20 and not the cam that causes the actual paper feeding swing of the pawl carrier 132. A third arm of the lever 136 has a contact surface 403 adapted under certain conditions to engage a similar surface 404 on a three-armed rocker 405 pivoted to the frame at 406. One laterally extending arm of this rocker carries a vertical rod 407 slidable through a hole in plate 53, and another arm carries a counterweight 408. Stops 409 on the rocker engage an abutment on the 25 frame to limit the swinging movement of the rocker in both directions.

The counterweight is adjusted so that the normal position of the parts is that shown in Fig. 41, where the rod 407 is raised and the contact 30 surface 404 clears the surface 403. In the absence of a cigar in a pocket of the disk 100, the rod 407 is pushed down by means to be described, swinging the rocker 405 to the position of Fig. 40 and causing the two contact surfaces to engage.

40 Since the thrust thus produced on the rocker 405 is substantially in the line of its pivot, the lever 136 will be locked, and the spring 401 will be unable to cause the roll 400 to follow the cam surface. Since it is the motion caused by the 45 spring that is effective in causing movement of the paper feed rolls, no sheet will be advanced. Upon the next rotation of the cam 402, the lever 136 will be given a slight turning motion in a direction clockwise as viewed in Fig. 40, freeing 50 the contact surfaces 403, 404, and permitting the rocker 405 to return to its normal position unless again restrained by the depression of the rod 407.

This rod is acted on by a finger 410 (Figs. 7 and 40) carried by an arm 411 freely pivoted at 55 412 to the plate 53. A second finger 413 is formed on the arm 411 directly above a rod 414 carried by a lever 415. Upon this lever is a cam roll 416 engageable with a crown cam 417 on the vertical cam shaft 74. The arm 411 overhangs the disk 60 100, and has a third finger portion or feeler 418 adapted to enter one of the pockets 110 unless restrained by the presence of a cigar. The rod 414 is lowered once during each wrapping cycle at a time when the disk 100 has stopped with one 65 of its pockets 110 in register with the feeler 418. If a cigar is in this pocket, the arm 411 cannot drop and the rocker 405 is not disturbed from its normal position of Fig. 41. If no cigar is present, the feeler encounters no resistance and the 70 arm will drop its weight, cause the rocker to shift to the position of Fig. 40 and prevent the feeding of a sheet of wrapping material as described previously. The arm is raised by the cam 417 in time to remove the feeler 418 from the pocket 75 before the disk resumes its rotation.

Summary

The operation of the machine has been described in the description of the several groups of mechanism and need not be repeated here in detail. For purposes of conciseness, the machine has been described directly in its preferred form, with no attempt to indicate with each group of mechanisms the numerous possibilities of change by the substitution of equivalent devices. It will be understood, however, that the invention is not confined to the structure described but also resides in the novel mechanical combinations as pointed out in the following claims.

80 'I claim:

1. A wrapping machine comprising a pair of end tucker plates movable simultaneously towards each other to form end tucks in the wrapper, said plates being of increased thickness on their ends towards the article.

85 2. A tucking plate for a wrapping machine making contact with the wrapper along one edge of the plate, said edge being of gradually increasing thickness in a direction towards the body of the article.

90 3. A tucking plate for forming tucks in a wrapper around a cigar, said plate being curved to fit the curved end of the cigar and making contact with the wrapper along the curved edge of the plate.

95 100 4. A tucking plate for forming tucks in a wrapper around a cigar, said plate being curved to fit the curved end of the cigar and making contact with the wrapper along the curved edge of the plate, said edge being of increasing thickness in a direction towards the body of the cigar.

105 5. A wrapping machine for cigars with tapered ends comprising a pair of tucker plates movable towards the cigar to form tucks in the wrapper, said plates being formed to fit the tapered ends of the cigar and forming tucks both in the portion of the wrapper around the curved ends of the cigar and in the extension of the wrapper beyond the cigar.

110 120 6. A wrapping machine for cigars with tapered ends comprising a pair of tucker plates movable towards the cigar to form tucks in the wrapper, said plates being formed to fit the tapered ends of the cigar and forming tucks both in the portion of the wrapper around the tapered ends of the cigar and in the extension of the wrapper beyond the cigar, said formed portions of the plates being of increasing thickness in a direction towards the body of the cigar.

125 130 7. A wrapping machine adapted to enclose articles in resilient wrapping material comprising means for folding a wrapper about an article leaving a tubular extension of the wrapper extending beyond the end of the article, opposed tucking elements engageable with opposite sides 135 of the wrapper end extension to make bellows folds therein, opposed end folders movable to engage the wrapper end extension at points between the points of engagement by the tucking elements, and timing mechanism constraining 140 the tucking elements and the folders for relative movements so that the folders partially close together prior to the separation of the tucking elements and complete their closing movement after the separation of said elements, whereby 145 the bellows folds will be preserved against the tendency of the resilient wrapping material to cause the folds to open up.

150 8. A wrapping machine for articles having curved ends comprising means for folding a

- wrapper around an article in tubular form leaving a wrapper end extension projecting beyond the article, means for flattening said end extension into a single fold extending at an angle to 5 the article, a folder shaped to conform to the end of the article, and means for causing relative movement between the article and the folder to cause the end of the fold to impinge end-on against the folder and to be folded simultaneously throughout its width against the article.
9. A wrapping machine folder comprising a stationary member having a surface curved in one direction only, and means for directing a wrapper flap end-on against said folder in the 15 direction of said curvature.
10. A wrapping machine comprising a pair of wrapping channels and a device for transferring partially wrapped articles from one channel to the other, said device comprising a pushing device normally located at one side of the path 20 of travel of the articles in the first channel, an opposed member normally spring pressed into said path but deflectable by the article, means for presenting said transferring device alternately to the two channels, means for grasping the articles and carrying them in a fixed path from the first channel into the transferring device, and means for ejecting the package from the transferring device into the second channel.
- 25 11. A wrapping machine comprising a wrapping channel, gripping jaws for grasping an article and conveying it along said channel, a yieldable plate device onto which the article is delivered by the gripping jaws, end holding members positioned opposite said yieldable plate normally out of path of articles delivered by said gripping jaws and against which the article is pressed by the yieldable plate as the article is released by the gripping jaws.
- 30 12. A cigar wrapping machine comprising a mechanism for folding around a cigar a strip of resilient material such as cellophane, leaving a tubular end extension of the wrapper at each end, a tucking device at each end of the cigar, presenting wrapper contacting edges converging in the direction of the end of the tubular wrapper to form tapering opposed bellows folds therein, oppositely reciprocable creasing members at each end of the cigar timed in their motion so 35 as to be in engagement with and to secure the tucked formation of the end extensions during the withdrawal of the tucking devices and then to crease transverse hinge lines in each of the tucked wrapper end extensions and to flatten and 40 crease said bellows folds, said creasing members also acting to partially bend over the flattened end extensions upon the creased hinge lines, a folder at each end of the cigar acting to complete the folding of the end extension about the 45 hinge line, and heating means for setting the folds in their folded condition.
- 45 13. A cigar wrapping machine comprising a mechanism for folding around a cigar having a tapered end a wrapper of resilient material such as cellophane, leaving a tubular extension of the wrapper at the end of the cigar, opposed folding members having wrapper engaging edges converging towards the end of the wrapper and movable into contact with opposite sides of the 50 tubular extension of the wrapper to form bellows folds therein, a pair of folders at the end of the cigar shaped to form when moved towards each other a creased hinge line in the tubular extension spaced from the end of the cigar, and 55 to flatten and partially bend the outstanding bellows folded tubular extension, means for reciprocating said last named folders in such timed relation that they meet to form the hinge line substantially at the longitudinal axis of the cigar, whereby the portion of the wrapper between the end of the cigar and the hinge line will be given a rigidity sufficient to stand the end thrust of the folding of the outstanding part of the extension, and a folder operable to turn the outstanding end of the wrapper extension about the hinge line and against the body of the wrapper without causing the wrapper to pull substantially against the end of the cigar.
- 60 14. A cigar wrapping machine comprising an intermittently rotatable turret, a plurality of grippers carried by the turret, means for delivering a partially wrapped cigar to the grippers at one station, means at another station for forming bellows folds and partially folding the bellows folded ends of the wrapper on lines spaced from the ends of the cigar, means at a third station to take the cigar from the grippers and to complete the formation of the end folds, and means for setting the wrapper folds by the temporary application of heat.
- 65 15. A cigar wrapping machine comprising a rotatable carrier, means for rotating the carrier step by step, a plurality of grippers spaced apart on the carrier, feeding mechanism for positioning a strip of resilient wrapping material such as cellophane adjacent a position of rest of the carrier grippers, a plunger reciprocable to force a cigar into said strip and to carry the assembled cigar and strip into the adjacent gripper, the strip being bent into U-form during such movement, a rear tucker movable to lay down upon the cigar one outstanding side of the U-shaped strip, a stationary folder positioned in the path of the second outstanding side of the strip so as to lay it down over the first side as the carrier rotates, whereby the strip is folded about the cigar with open tubular ends extending beyond the cigar, a folder positioned adjacent each end of the cigar and presenting oppositely facing wrapper blades each engageable with one side of one open tubular end of the wrapper substantially centrally thereof, and actuatable simultaneously to cause the four blades to press opposite central portions of the open tubular ends of the wrapper inwardly and thus form bellows-like 70 tucks therein, a pair of opposed creasing members positioned adjacent each end of the cigar and movable to engage opposite sides of the wrapper end extensions at points between the tucking blades, mechanism for actuating the bellows-tuck folders and the creasing members in timed sequence so that after the bellows tuck folders have formed tucks in the end extensions the creasing members will by their engagement with the end extensions prevent the tucks from 75 springing out due to the resiliency of the wrapping material, and said creasing members will thereafter crease the tucked end extension on a hinge line spaced from the end of the cigar and will flatten and crease the bellows-like tucks in the projecting end extensions, said creasing members acting also to partially fold the flattened end extension upon the hinge line, a folder engageable with the end extension beyond the hinge line to fold said extension over upon the body of the cigar, and means for heating the folded ends of the wrapper to give them a permanent set in their folded condition.
- 80 16. In a wrapping machine, means for supporting a partially wrapped article with a tu-

- tubular wrapper extension projecting therefrom, a reciprocable creasing plate movable in a plane intermediate of and transverse to the tubular extension and having its leading end formed 5 with a creasing edge, means for reciprocating the plate to an active position where it has partially folded the tubular extension, a second oppositely reciprocable member, a roller carried by the second member and yieldingly mounted 10 with respect to the plate, and means for reciprocating the second member to cause the roller to impinge upon the creasing edge of the plate when the latter has reached its active position and thereafter to iron down the extension over 15 the surface of the plate to crease the extension laterally and longitudinally and to bend it at substantially right angles to its original position.
17. In a cigar wrapping machine of the type having a turret rotating about a vertical axis 20 and provided with a series of downwardly opening radially elongated grippers arranged to receive a partially wrapped cigar, together with a folding throat and a plunger for elevating an article and a wrapper through the throat to a 25 position to be grasped by a gripper; a vertically movable upper wrapper retaining plunger reciprocable into the throat to bear upon the wrapper and then upwardly between the jaws of the opened gripper, and a mounting for the upper 30 plunger permitting yielding movement in the direction of rotative movement of the grippers.
18. In a cigar wrapping machine of the type having a turret rotating about a vertical axis and provided with a series of downwardly opening radially elongated grippers arranged to receive a 35 partially wrapped cigar, together with a folding throat and a plunger for elevating an article and a wrapper through the throat to a position to be grasped by a gripper; a vertically reciprocable 40 support, a rotatable member on the support, a parallel linkage carried by the member, an upper plunger carried by the linkage, means for reciprocating the support so that the upper plunger descends into the folding throat and then rises 45 through the opened gripper while maintaining yielding contact with the wrapper stretched across the cigar being elevated by the first-named plunger, and means for holding said rotatable member yieldingly in position with the upper 50 plunger in alignment with the lower plunger.
19. In a wrapping machine of the type having means for draping a wrapper over an article in inverted U-form; an open ended stationary guide, a bottom folder reciprocable on the guide, a 55 folder operating member, and a detachable connection between the folder and the member, whereby the folder can be slipped from the open ended guide for removal from the machine.
20. In a wrapping machine of the type having 60 means for draping a wrapper over an article in inverted U-form; an open ended stationary guide, a bottom folder reciprocable on the guide, a folder operating member, a cam engaging the member so as to move it positively away from 65 folding position, a spring engaging the member to hold it against the cam and thus to cause its folding movement, a rigid support projecting from the folder, a link pivoted to the folder, and a pin connecting the operating member and the link 70 and resting upon said rigid support, whereby the folder can be slipped from the open ended guide and detached from the pin for removal from the machine.
21. In a wrapping machine, means for for- 75 warding an article and its encircling wrapper
- through a path, means operating on the wrapper while the article is in said path for bellows folding its end portions and subsequently flattening the bellows folded end portions and folding them at right angles, means for grasping the body of the article and moving it at right angles to the plane of said path, and stationary curved end folders upon which the folded ends impinge end on during said movement to turn them under the article.
22. In a wrapping machine, means for forwarding an article and its encircling wrapper through a path, means operating on the wrapper while the article is in said path for bellows folding its end portions and subsequently flattening the bellows folded end portions and folding them at right angles, means for grasping the body of the article and moving it at right angles to the plane of said path, stationary curved end folders upon which the folded ends impinge end on during said movement to turn them under the article, a delivery chute in line with said folders, a plunger feeding the article along the delivery chute, stop pins spaced apart a distance greater than the width of the plunger and movable into the delivery chute, and means for operating the stop pins to move them out of the chute during the advance of an article by the plunger and back into the chute before the plunger moves back, thereby to prevent retrograde movement of the article without interfering with the movement of the plunger.
23. In a wrapping machine, a delivery chute, a plunger of less width than that of the articles, means for reciprocating the plunger periodically, 110 a pair of stop pins spaced apart a distance greater than the width of the plunger, and means for moving the pins positively out of the chute during the advance of an article by the plunger and back into the chute before the plunger moves back, thereby to prevent retrograde movement of the article without interfering with the movement of the plunger.
24. In a wrapping machine, a delivery chute, a plunger, means for reciprocating the plunger periodically, a stop device, the plunger and the stop device being mutually so constructed and arranged that the presence of the stop device in the chute does not interfere with the movement of the plunger, and means for moving the stop 115 device positively out of the chute during the advance of an article by the plunger and back into the chute before the plunger moves back, thereby to prevent retrograde movement of the article without interfering with the movement of the plunger.
25. In a wrapping machine, a wrapper folding station, a chute through which the article is moved in relation to that station, a plunger for moving the article along the chute, a link pivotally mounted at one end at a point fixed with respect to the chute and pivotally connected to an intermediate point of the plunger at its other end, a second link of shorter length than the first and substantially parallel thereto, said second link being pivotally mounted at one end at a point fixed with respect to the chute and pivotally connected at its other end to the plunger on the remote side of the first link from the article contacting face of the plunger, and means 130 for reciprocating the plunger, the described linkage operating to cause the article contacting face of the plunger to travel in a substantially straight line during its reciprocation.
